UNITED STATES PATENT OFFICE.

BENJAMIN BRODIO, OF NEW YORK, N. Y., ASSIGNOR TO THE SUPERHEATER COMPANY, OF NEW YORK, N. Y., A CORPORATION OF DELAWARE.

FEED-WATER-TEMPERATURE REGULATOR.

Application filed October 30, 1923. Serial No. 671,811.

This invention relates to economizers for heating the feed water supplied to steam boilers. With the use of such economizers it has been found that when the temperature 5 of the feed water passing to the economizer falls below a certain point, the hot flue gases are unable to raise the temperature of the water within the economizer tubes to a point sufficient to prevent the formation of a condensate on the outside of said tubes. This condensate causes corrosion and "pitting" of the tubes and the consequent rapid deterioration of the economizer, which is much more serious with economizers constructed 10 of steel than when they are constructed of cast iron. The tendency of modern steam engineering is towards the use of higher pressures, which necessitates the use of steel economizers to replace the cast iron economizers, almost universally used heretofore, therefore the prevention of the formation of the condensate becomes of very great importance. A further difficulty caused by the presence of the condensate is the collection 15 or absorption by the condensed water of soot and fumes from the flue gases which causes a deposit to collect upon the tubes, thereby lowering the efficiency of the economizer.

20 The principal object of the present invention is to provide a new and improved construction of great simplicity by means of which the feed water delivered to the economizer will be raised to the temperature required to prevent the formation of the 25 aforementioned condensate.

Another object is to provide a means for automatically rendering the device operative or inoperative when the temperature of the 30 feed water passing to the economizer falls below or exceeds respectively a certain critical point necessary to insure a temperature of the water within the tubes above which no condensate can be formed.

35 For the accomplishment of these and such further objects as will be apparent to those skilled in the art to which this invention appertains, my invention consists in the construction, combination and arrangement of parts, an embodiment of which is herein- 40 after more specifically set forth and is shown in the accompanying drawing forming a part hereof, but it will be understood that changes, variations and modifications may

be resorted to without departing from the 55 spirit of my invention.

Fig. 1 of the drawing represents a diagrammatic showing of an economizer having a system of piping connected therewith for carrying out my invention, and Fig. 2 is an 60 enlarged sectional detail.

Referring to the drawing, the numeral 10 indicates an economizer located, in accordance with the usual practice, within the path 65 of the flue gases from the boiler 12 and having the usual feed water tubes 11 therein.

The feed water is supplied to the economizer from the hot well 13 by means of a feed water pump 14 having its suction side connected to the hot well by means of the pipe 15 and its pressure side connected to the inlet of the economizer by means of the inlet pipe 16. The feed water passes from the outlet of the economizer to the boiler by the 70 outlet pipes 17 in the usual manner.

A by-pass 18, which is connected with the outlet pipe 17 and with the pipe 15 on the suction side of the pump, serves to deflect a portion of the heated water passing from the economizer and to mix said portion with 75 the colder water drawn from the hot well, thereby causing the temperature of the feed water passing to the economizer to be raised to the required point.

80 A thermostat 19, of any suitable construction is interposed in the pipe 16 and suitable connections 20 are made from the thermostat to a valve 21, interposed in the by-pass 18, to cause said valve to be opened or closed when the temperature of the feed 85 water passing through pipe 16 falls below or above a certain predetermined point, thus causing the by-pass 18 to be placed automatically in operation.

85 Because of the frictional losses due to the passage of the water through the economizer tubes the pressure of the water at the exit of the economizer is less than at the inlet thereof, consequently it is necessary to connect the by-pass 18 to the suction side of 90 the pump to insure the passage of the hot water through said by-pass.

The operation of the device is as follows: Assuming that the feed water being pumped 95 from the hot well drops below a certain critical temperature, for example 140°, and that the thermostat 19 is set to open valve 21 at such temperature, a portion of 100

the hot water issuing from the economizer will be drawn through the by-pass 18 to mingle with the cold water passing through pipe 15, thereby causing its temperature to be raised to a sufficient degree to insure a temperature within the economizer which will prevent the formation of a condensate on the tubes thereof. If the feed water is above the critical temperature, valve 21 will be closed by the thermostat and no water will flow through by-pass 18. The capacity of the by-pass obviously should be so proportioned as to insure the passage of a sufficient volume of hot water to raise the temperature of the water passing through the pump 14 to the required degree.

I claim:

1. The combination with an economizer having a feed water inlet and a feed water outlet and a feed water pump, connected with said inlet of a by-pass directly connected with the outlet of the economizer and the suction side of the pump to cause a portion of the hot water issuing from the economizer to be withdrawn by the suction of said pump and mixed with the feed water flowing to said pump, a valve for controlling the flow of water through said by-pass, and a heat-responsive device associated with the pipe line between the economizer and the by-pass controlling the operation of said valve.

2. The combination with an economizer

having a feed water inlet and a feed water outlet and a feed water pump, connected with said inlet, of a by-pass directly connected with the outlet of the economizer and the suction side of the pump to cause a portion of the hot water issuing from the economizer to be withdrawn by the suction of 40 said pump and mixed with the feed water flowing to said pump, and means to render said by-pass operative or inoperative automatically in accordance with variations of the temperature of the feed water passing 45 to said economizer.

3. The combination with an economizer having a feed water inlet and a feed water outlet, and a pump connected with said feed water inlet to supply feed water thereto; 50 of a by-pass directly connected with the outlet of said economizer and the suction side of said pump to cause a portion of the hot water issuing from said economizer to be withdrawn by the suction of said pump and 55 mixed with the feed water flowing to said pump, a valve within said by-pass and a thermostat interposed between said pump and inlet in the path of the feed water flowing to said inlet and connections from said thermostat to said valve to cause said valve to be operated in response to variations of the temperature of the feed water passing to said economizer above or below a certain predetermined critical point.

BENJAMIN BROIDO.
